UNITED STATES PATENT OFFICE.

VALENTINE W. MILLER, OF FONDA, IOWA.

GRAIN-DOOR FOR CARS.

1,303,832.

Specification of Letters Patent. Patented May 13, 1919.

Application filed October 15, 1917. Serial No. 196,637.

To all whom it may concern:

Be it known that I, VALENTINE W. MILLER, a citizen of the United States, and resident of Fonda, Pocahontas county, 5 Iowa, have invented a new and useful Grain-Door for Cars, of which the following is a specification.

The object of this invention is to provide an improved grain-tight door for use on 10 freight cars when said cars are employed for the transportation of grain.

A further object of this invention is to provide an improved multiple-section grain door the sections of which are adapted for 15 successive movement to operative or inoperative position.

A further object of this invention is to provide improved means for slidingly mounting sections of a grain door for vertical movement in the door frame and for horizontal movement to inoperative position at the top of the car.

A further object of this invention is to provide improved means for mounting a 25 grain-door in a car.

My invention consists in the construction, arrangement and combination of elements hereinafter set forth, pointed out in my claim and illustrated by the accompanying 30 drawing, in which—

Figure 1 is a longitudinal vertical section through a portion of a car, showing one of my improved grain-doors in closing position. Fig. 2 is a cross-section of a car 35 equipped with my improved doors, two sections or leaves of one of the doors being shown in suspended or inoperative position. Fig. 3 is an outer elevation of a portion of a car door frame and grain door therein. Fig. 4 is an outer face view of one of the 40 door sections detached, a portion being broken away to economize space. Fig. 5 is a horizontal detail section showing the means of slidingly mounting the door sections in the frame. Figs. 3, 4 and 5 are on a scale enlarged relative to Figs. 1 and 2.

In the construction as shown the numeral 10 designates sills supporting floor boards 11, and the numeral 12 rafters carrying a 45 roof 13 of a freight car of any common or well known construction, the side walls 14, 15 whereof are formed with doorways each having jamb posts 16, 17 and a header 18.

Metal plates 19, 20 are mounted against 50 and fixed to the opposed faces of the jamb posts 16, 17 and said plates are formed with

vertical slideways 21, preferably in the form of substantially T-shaped grooves or channels opening to the opposed faces of said plates. A plurality of separate door sections 22 are provided for each of the doorways of the car and preferably are composed of planking cut to the proper length to fit snugly between the jamb posts and slide with their ends in contact with the 60 plates 19, 20, and adapted to rest in closing position one above another in the doorway. Each door section 22 is provided at its ends with projecting headed studs 23, 24, which may be formed of bolts or lag-screws seated 65 in said door sections, the studs extending within and having their heads vertically 70 slideable in the grooves 21. An angle iron 25 is secured to end portions of each door section 22 and has one flange overlying the end 75 and the other flange overlying the end portion of the outer face of each of said sections. The long margins of the door sections 22 preferably are formed with ogee 80 curves, or are dovetailed or otherwise formed with interlocking surfaces to provide tight joints between the sections, as illustrated best in Fig. 2.

Metal posts 26, 27 are mounted against the opposing faces of the plates 19, 20 and 85 adjacent the outer margins thereof, and said posts preferably are formed of angle irons having one flange each projected toward the center of the doorway and serving as a stop to prevent outward displacement 90 of the door sections, and as a brace and support for said sections as well as a reinforcement to the grooved plates 19, 20.

Plates 28, 29 are mounted transversely 95 across the top of the car in the same vertical planes as the plates 19, 20 and are supported in any suitable manner, as by certain of the rafters 12. The plates 28, 29 are formed on their opposed faces with grooves 30 forming continuations of and 100 connecting the vertical grooves 21 of the vertical plates, and of the same shape in cross-section.

In practical use the door sections are mounted as shown with the headed studs 105 23, 24 extending and slideable within the grooves 21 and 30, and to close the door openings said sections are successively moved to position within the doorways and filling the spaces between the jamb posts thereof, 110 the angle posts 26, 27 serving to form tight joints between the ends of the door sections

and the plates 19, 20. The door sections are first moved to the bottom of the doorway and then successively added as needed. Cleats 31, 32 may be secured to the car floor 5 across the doorways in engagement with the lower margins of the lowermost door sections 22 and serving as stops, reinforcements and joint-closing members therefor. When it is desired to move any or all of 10 the door sections to inoperative position, to open or partially open the doorways, said sections are successively, beginning with the uppermost, moved upwardly in the doorways, the headed studs traveling in the 15 grooves 21, to the tops of the doorways, and then are moved laterally inwardly toward the center of the car, the headed studs traveling in the communicating grooves 30 and supporting said sections between the 20 plates 28, 29. The studs 23, 24 preferably are above the centers of the door sections, as illustrated in Fig. 4, so that said sections tend to hang in vertical positions between the plates 28, 29, and they may be positioned 25 side by side in compact relations therebetween, entirely out of the way of laborers or others in the car, and out of the way of loading of the car when it is used for loads other than grain. The horizontal grooves 30 preferably are formed with depressed 30 central portions or seats 30^a (Fig. 2) extending transversely of the car and adapted to receive the door sections when not in use and suspend them by their studs and prevent 35 accidental displacement of the door sections from their inoperative positioning. The horizontal grooves 30 also preferably are

formed at their ends with depressed horizontal portions 30^b at a lower level than the main portions of said grooves and below 40 the headers 18, to facilitate the introduction of sections entirely to the tops of the doorways, by horizontal sliding movement beneath the headers.

Notches 33 are formed in the outer flanges 45 of the angle irons 25 on the door sections, and notches 34 are formed in the outstanding flanges of the angle posts 26, 27, and when said door sections are in place in the doorways their notches 33 overlap upon but 50 are at slightly lower elevation than the notches 34 of the posts. A pry bar or other instrument is adapted to be inserted in the notches 34 of the posts, in engagement with the upper margins of the notches 33 of the 55 door sections, to facilitate raising of the door sections when the car is loaded, the pry bar fulcruming or bearing on the lower margins of the notches 34 in such operation, as will be clearly understood from the showing in 60 Fig. 3.

I claim as my invention—

A grain-car door, comprising jamb members formed with vertical grooves, angle bars on said jamb members formed with 65 transverse notches, separate door sections mounted for vertical sliding movement between said jamb members and formed with headed studs adapted to travel in said grooves, and angle plates fixed to and overlying end portions of said door sections and formed with transverse notches overlapping 70 at times the notches in the angle bars.

VALENTINE W. MILLER.
